CAN OPENER

Walter W. Edlund, Burlington, Vt.
Filed Nov. 21, 1958, Ser. No. 775,409
10 Claims. (Cl. 30—9)

This invention relates to improvements in can openers and particularly to a manually operated heavy duty can opener adapter for use in restaurants and other commercial establishments. These heavy duty openers having manually operated "crank" handles have been employed in such establishments for many years and have received rather wide acceptance. Such can openers are of two general types in so far as their operation is concerned, namely: The two handle type which requires the operation of two handles in effecting the opening and release of the can, and the single handle operated type. The latter are preferable from the user's standpoint but have heretofore been provided with straight edge knives. Such knives are not as satisfactory as disc knives. However, no one has heretofore devised a satisfactory disc knife single handle opener. One object of this invention is to provide a single lever operated manual can opener employing a rotary knife.

Heretofore known can openers of the type to which the present invention relates, embodying disc cutters, are at a disadvantage in that the cutters require adjustment from time to time and that the cutters when in cutting position are fixed with respect to the gears or other means employed for propelling the can. Another object of the instant invention is to provide an opener in which adjustment of the cutting blade with respect to the propelling means is unnecessary and a further object is to provide an opener in which the cutting blade is resiliently positioned. This latter advantage will prevent damage and insures an easier operation.

A further object of the invention is to provide a can opener as set forth in the preceding objects embodying a casting which has a clean exterior, is relatively simple and compact and can be relatively easily and cheaply cast. Heretofore known castings providing the main housings for the openers are relatively complex and do not provide a neat exterior.

A further object of the invention is to provide a can opener which is readily and economically adaptable to an exterior formation which will result in a pleasing appearance for the opener. Heretofore known can openers of the instant type embodied projections and attachments or screws or other devices which detracted from the appearance and militated against the formation of a clean neat modern design opener.

A still further object of the instant invention is to provide an opener including a housing structure which substantially completely encloses the opener and in which the housing construction is neat, clean and free from projections.

Another advantage of such construction as set forth in the preceding objects is to provide an opener which will remain clean, which is less likely to pick up dirt, foreign particles, etc., and which also can be easily cleaned in the event such particles should be received therein.

A further object of the instant invention is to provide an opener as set forth heretofore which does not require attachments for completing the casting or forming can stops or other means and in which, instead, a unitary casting is employed and the stop means for positioning the can are formed integrally therewith.

It is well known that it is necessary and customary to move the knife utilized in cutting the can, with respect to the means for impelling the can past the knife, so as to insert and remove the can from the opener. One

2

of the two handles mentioned above as used with prior known openers is provided for this purpose. The latter handle controls swinging movement of the knife with respect to the impelling means, usually a gear, and the usual crank handle is provided for rotation of the gear like impelling means, once the knife is in cutting position. With such an opener the hand of the operator must be shifted from the knife moving means to the impeller operating means and back to perform a complete cutting operation, including insertion and removal of the can or connection and disconnection of the can from the cutter. Accordingly one of the objects of the instant invention is to provide a one-hand operated opener having only one lever or its equivalent whereby the other hand of the operator or user of the device is free for manipulation and placement of the can with respect to the opener, etc.

An additional object of the invention is to provide a one-hand operated opener having an operating handle which functions to rotate the can impelling means together with means operated by the same handle for moving the cutter with respect to the can impelling means.

Still another object of the invention is to provide an opener accomplishing the foregoing objects wherein the connection between the cutter and the impelling gear means is such that the opener can be easily operated both during normal cutting and in the connection and disconnection of the can and opener.

A further object of this invention is to provide an opener construction with which cans can be readily inserted into cutting relationship with the opener with much greater ease than heretofore possible.

An additional object of the invention is to provide an opener as set forth in the preceding object with which effective proper cutting contact with the can is achieved by simply bringing the can into bearing relationship against a portion of the opener and the opener is then brought downwardly onto the can. Through a continued downward movement of the opener the can is received in proper cutting relationship and the cutter is properly engaged with the can. With the heretofore known apparatus of a similar type if the can cutting or puncturing mechanism is not properly positioned the can is apt to hang up on the opener as the latter is brought down into a cutting relationship with the can. This cannot occur however with the instant construction since, due to the single handle operating structure, proper relationship of the cutting knife to the can for puncturing is assured when the opener is raised.

It is also noted that with heretofore known constructions the cans may "hang up" even if the puncturing mechanism is properly positioned for insertion of the can. A further object is to insure that this will not occur; that once the opener is raised the cutter and can impeller are properly positioned and that the opener can then be simply brought down onto the can.

One other object of the invention is to provide a resiliently positioned cutter which can accommodate to irregularities and which is properly maintained in cutting position.

These and other objects and advantages will become apparent from the following description and the accompanying drawings in which:

FIGURE 1 is a side elevational view of an opener constructed in accordance with the invention.

FIGURE 2 is a front elevational view.

FIGURE 3 is a sectional view taken along line 3—3 of FIGURE 2 showing the elements in can opening position.

FIGURE 4 is a view similar to FIGURE 3 but showing the parts in a different relationship.

FIGURE 5 is a sectional view taken along line 5—5 of FIGURE 3.

FIGURE 6 is a sectional view taken along line 6—6 of FIGURE 3.

FIGURE 7 is a bottom view partly in section of a knife holder taken along line 7—7 of FIGURE 3.

FIGURE 8 is a top sectional view taken in the direction indicated by line 8—8 of FIGURE 3 and showing a support.

FIGURE 9 is a side elevational view of the opener in position in its supporting base and showing a can, which is being placed in position for cutting, initially striking a stop.

FIGURE 10 is a sectional side elevational view similar to FIGURE 9 but showing the can as it moves upwardly along the stop into cooperation with the knife.

FIGURE 11 is a view similar to FIGURE 10 but showing the can and opener in cutting position.

Referring now in particular to the drawings:

A can opener constructed in accordance with the instant invention has a housing 10. The latter comprises a pair of spaced side walls 12 and 14, and a connecting wall 16. The latter wall forms the rear 18 and top 20 of the housing. A front bridging wall 22 is positioned adjacent the front of the housing and also interconnects the side walls 12 and 14. The front bridging wall 22 extends practically half way up the front of the housing. The front wall 22 also merges at its bottom into a support 24. In the preferred embodiment this is a post of the type that has been known in the art and utilized to adjustably attach the opener to a platform or base. In FIGURE 9 the co-operation of the post and its base is illustrated. Similar structure is also shown in Patent No. 1,537,110 to Walter W. Edlund dated May 19, 1925 and Edlund Patent No. 1,713,823 dated May 21, 1929. The walls 12, 14, 16 and 22 define a chamber 26 having an upper and forward opening 28, and a lower rear opening 30. The opener housing 10 is preferably formed of a casting with all the above described walls being integral. Further, preferably the post 24 is also formed as a casting integral with the housing 10. However, it is apparent that the post 24 or other support means can be connected to the housing 10 by other suitable means such as is known in the art and also that the housing can be formed by other methods.

The front wall 22 has a stepped opening 32 comprising a first chamber having a shoulder 34, a connecting bore having a shoulder 36 and a third bore 38 connecting to the second bore. The bored openings providing the shoulders 34, 36 and the bore 38 are preferably aligned and are all concentric of a single axis. A stepped bushing 40 is received in the bore 38 and bears against the shoulder 36. Preferably there is a tight fit between bore 38 and the bushing. The bushing occupies all of the third bore and stepped opening providing the shoulder 36. The bushing has a preferably central shaft receiving opening 42. The rear wall 18 of the housing 10 has a preferably cylindrical opening 44 the axis of which is aligned with the axis of the bore 42. A bushing 46 is slidably received within the opening 44, and an arbor 48 extends through an arbor receiving opening 50 in the bushing 46 and the arbor opening 42 in the bushing 40. The arbor is rotatably received in both bushings. The arbor is preferably stepped to provide a rear arbor portion 52 and a front arbor portion 54, as well as a shoulder 56. The shoulder 56 bears against the shoulder 58 of the stepped bushing 40. The front arbor portion 54 projects forwardly of the bushing 40 and the front bridging wall 22, and that portion which does so project forward is threaded as indicated by reference character 60. A gear wheel 62 having peripheral teeth 64 is threaded onto this projecting portion into abutment with the bushing and closely adjacent the front face of the wall 22. Substantially all of the gear is received within the recess 65 provided by the side walls 12, 14 and the front wall

22. Substantially only the upper portion of the gear projects forwardly of the housing walls 12 and 14. At its rear the arbor is provided with a transversely extending pin 66 and is formed so as to provide a pair of parallel shoulders 68 and 70. The handle 72 has a bifurcated end 74 which closely fits with the shoulders 68 and 70 and receives the pin 66 in a manner such as to pivotally mount the handle for pivotal movement about an axis extending transversely of the arbor 48. The bifurcated end portions of the handle are provided with a pair of shoulders 76 and 78 adapted to bear against the bushing 46. The shoulders 76 and 78 are positioned at different radial distances from the center of the pin 66 and the handle as mentioned above is pivotal about this pin. Further, the shoulders 76 and 78 are at right angles to each other and the handle can be rotated through 90 degrees from a position in which the shoulder 76 bears against the bushing 46 to a position in which the shoulder 78 bears against the rear wall of the bushing 46. As a result the bushing in order to accommodate this movement must be capable of movement along the arbor 48, and a free sliding fit is preferred between the bushing 46, the arbor 48, and the housing 10. The bushing is normally maintained in the position illustrated in FIGURE 3 by resilient means hereinafter described, but will move to the position illustrated in FIGURE 4 when the handle is rotated in the direction indicated by the arrow 80.

A knife holder 82 is received in the housing 10. This knife holder comprises a front wall continuation portion 84 which is normally adapted to present the appearance of a continuation of the front bridging wall 22 upwardly to the top of the housing. Wall portion 84 normally closes the inner chamber 26 adjacent its upper end preventing the entrance of dirt, etc. The knife holder further comprises a rearwardly extending portion 86 and a forwardly projecting boss 88. The forwardly projecting boss extends downwardly at an angle of approximately 41 degrees with respect to the front wall continuation portion and is turned with respect to the vertical plane containing the arbor 48 so that it extends forwardly thereof toward the feed-in side 89 of the opener at an angle of approximately 7 degrees. As illustrated in FIGURE 3 the rearwardly extending portion 86 extends at an angle of approximately 90 degrees with respect to the front wall continuation portion 84. The feed-in side is to the right side of the cutter in FIGURE 2, and is the side from which the can rotates toward the cutter.

A bifurcated arbor receiving portion 90 projects downwardly from the rear of the rearwardly extending portion 86 of the knifeholder 82. The legs 92 and 94 of portion 90 project down on opposite sides of and thus receive the arbor 48. The knife holder 82 is pivotally mounted within the housing 10 by means of a shaft 96 which is formed of a rivet extending transversely through the side walls 12 and 14. The knife holder is readily pivotal on the shaft 96. The legs 92 and 94 in the normal position of the knife holder 82, which is the position illustrated in FIGURE 3, extend substantially transversely across the arbor and present forward faces against which is positioned a washer 98. A like washer 100 is positioned against the shoulder 34 within the recess there adjacent. A compression spring 102 extends between the two washers and normally urges pivotal movement of the knife holder through the medium of the bifurcated portion 90, counterclockwise about the shaft 96. This movement is limited to that in which the front wall continuation portion 84 extends substantially parallel to the front edges of the side walls 12 and 14 by means of a shoulder 104 which extends across the top of the front bridging wall 22 and a mating shoulder 106 which is formed by the lower edge of the boss 88. The lower edge of the boss 88 and the wall portion 84 substantially join each other in the plane of shoulder 106. Shoulder 104 slopes toward the front of the housing and is substantially parallel to the boss 88 when the latter is in the position illustrated in FIGURE 3.

The rear of the legs 92 and 94 are provided with raised cam like vertically curvilinear shoulders 108 and 110 respectively. These are normally urged by the spring 102 into contact with the bushing 46. The parts are in the relative position illustrated in FIGURE 3 when the can opener elements are in normal operating position with a can received between the gear wheels and cutter, or when the opener is merely at rest. The spring 102 normally maintains this relative positioning of the parts.

The boss 88 provides a front shoulder 112. The rear of the knife holder is formed so as to provide a shoulder 114 parallel to the shoulder 112 and also to provide a recess 116.

A knife holder shaft 118 extends through a bore 120 substantially perpendicular to the shoulders 112 and 114. The shaft has a reduced forward end 122 and a reduced rearward end 124. The latter end is threaded. The length of the central portion 126 is substantially the same as that of the shaft receiving opening 120. A disc knife 128 is mounted on the forward reduced end 122 and abuts against the shoulder 112 of the boss 88 and the central portion 126 of the shaft. The knife is held in place by a retaining ring 129. The knife has a can lip receiving peripheral groove 130.

A washer 132 is received on the rearward reduced end 124. A spring 134 bears against this washer and a lock nut 136. Nut 136 maintains the parts in assembled relationship. The spring 134 urges the knife and shaft resiliently against the shoulder 112.

When the elements are in normal operating position the gear wheel rim projects into the lip receiving groove, but is spaced therefrom sufficiently to receive the lip of a can, and the blade extends downwardly into the top of the can as illustrated in FIGURE 11. The upper wall 20 is provided with a depending bead 138 which extends downwardly toward the front wall continuation portion 84 of the knife holder 82 to cooperate with the latter to close the inner chamber 26.

The housing 10 is provided with a pair of stops or rests 140 and 142. The stop or rest 140 consists of a projection laterally of the front face of the side wall 12 forming a forward surface substantially co-planar with the latter. The stop 142, on the contrary, in addition to constituting a portion extended laterally of the vertical surface of the front edge 146 of the side wall 14 has an outward projection extending outwardly of the forward edge 146 and defining a contact surface 144. The surface 144 defined by the stop 142 is substantially parallel to the shoulders 34, 36 and the front shoulder 148 of the front bridging wall 22 and extends upwardly substantially in horizontal alignment therewith alongside the gear wheel 62. The surface 144 is started low enough on the side wall 14 so that the surface 144 extends outwardly forwardly of the opener to a distance substantially in alignment with the maximum forward projection of the upper end of the gear wheel. Note that the gear wheel presents at its front a frustoconical shape 150 and thus only its upper portion projects forwardly of the surface 144. The surface 144 merges with the front edge 146 and also merges with the front edge 152 of the post 24. The shoulders 140 and 142 guide the can during its rotation relative to the opener and further as is apparent from an examination of FIGURES 9-11 serve to guide the can into proper cutting position.

FIGURE 9 illustrates the relative position of the opener and its post 24 with respect to the base 154. The latter is a type which has been employed heretofore in mounting these heavy duty can openers. It is apparent that the opener is adapted to take a number of sizes of cans.

In opening a can the following steps are performed: The handle 72 which is noted has a rotatable knob 156 is swung counter clockwise as indicated by the arrow 80 and subsequent thereto the post and head are moved upwardly with respect to the base. This movement of the handle causes a clockwise rotation of the knife holder

which raises the knife from the gear. The can is then inserted beneath the opener and against the surface 152 of the post. After which the post and opener are moved downwardly. When they are in the position indicated in FIGURE 9 the can strikes the stop and positioning surface 144 so that continued downward movement of the opener urges the can away from the opener on the feed-in side. This causes the can to clear the gear wheel 62. It is noted that the knife is in the position illustrated in FIGURE 4 and the can bead is thus cammed upwardly into connection with the knife. In FIGURE 4 the can is illustrated adjacent the top of the stop with the rim having entered into the rim grove 130. The knife now rests on the can cover. Next the handle is swung downwardly into the position in which it is illustrated in FIGURE 3. As this is done the elements including the can rim assume the relative positioning illustrated in FIGURE 10 with the knife still pressing against the can top, but also pressing the can bead against the gear. Note that the can side is also pressed against the gear face.

Now upon rotation of the handle the knife will snap into cutting relationship and the elements will take the position illustrated in FIGURE 11. A distinctly audible snap is heard as the knife initially cuts into the can. In this position the can rim bears against the stops 140 and 142. Upon continued rotation the rim is moved across the teeth of the gear wheel 62 and the top is thus severed by the knife. The springs 134 and 102 resiliently maintain the cutter in proper position but enable automatic adjustment to any irregularities.

With this construction it is never necessary to keep adjusting the cutter wheel. Further, different sized and shaped cans are all accommodated with the one setting.

When the can opener has completed its can opening operation it is apparent that the handle is moved upwardly and at the same time the head is raised. All this can be accomplished while holding the can in position, thus preventing spilling and facilitating instant detachment of the can from the opener.

The stop construction and knife and gear wheel relationship therewith facilitates placement of the cans. It is only necessary to slide the can up against the post 24 and lower the opener in order to obtain a correct positioning of the can. The can will always be cammed into proper cutting position. This is an obvious advantage over openers where such construction is not provided. Note that the cutting edge of the cutter 128 extends outwardly a substantial distance relative to the gear wheel and shoulder 144 as the opener is being moved down along the can and the rear edge 158 of the knife which is a beveled edge will cam the can rim bead into proper relationship to be properly engaged by the gear wheel and cutter. It is only necessary, as pointed out hereinbefore, to swing the handle of the opener down after the can has been inserted beneath the opener and then crank the handle and the cutting of the cover will be effected.

While I have shown and described a preferred form of my invention it will be apparent that many changes in details and form can be made, and therefore I claim an exclusive right to all modifications and changes in form coming within the scope of the appended claims.

I claim:

1. A can opener comprising a housing, said housing having a chamber, a bridging wall positioned in said chamber adjacent one side thereof, said housing having a front face formed by a pair of side walls, said bridging wall being adjacent said front face and being inclined with respect thereto in a vertical plane, said bridging wall and said housing defining a recess, a gear wheel rotatably received in said recess and having an upper portion of its periphery projecting outwardly of said front face with its lower portion being received to the rear of said front face within said recess, a knife holder

positioned in said chamber, a knife supported by said knife holder and normally projecting outwardly of said front face, said knife being in relationship with said gear wheel for receiving a can therebetween for severing a portion of said can, said knife holder normally bearing on said bridging wall and extending laterally within said chamber substantially intermediate the two side walls adjacent said front face and having an upstanding portion forming a continuation of said front face in a vertical plane upwardly above said bridging wall but being spaced from said side walls of said housing sufficiently for movement of said knife holder with respect thereto, means for moving said knife holder and the knife connected thereto with respect to said gear wheel for the insertion and removal of a can therebetween.

2. A can opener comprising a housing, a gear wheel rotatably supported on said housing, said housing having a front face, said gear wheel having the upper peripheral portion thereof projecting outwardly of said front face, a rotary knife means cooperable with said gear wheel for opening a can with said gear wheel and knife having cooperating recess means for receiving a can portion therebetween, a pair of stop means positioned laterally on opposite sides of said gear wheel, one of said stop means being positioned on the feed in side of said gear wheel and knife and the other being positioned on the feed out side, the stop on said feed in side defining a planar surface angling vertically with respect to said front face of said housing, the upper portion of said surface terminating at approximately the height of said can receiving recess means defined by said gear wheel and said knife, said surface extending throughout its length a distance from said face sufficient to urge a can rim moving vertically upward thereagainst outwardly with respect to said gear wheel on said feed in side of said wheel.

3. The apparatus of claim 2 wherein said housing is supported on a post slidably positioned within a base member, said post having a front face disposed substantially in the same vertical plane as the front face of said housing with said feed in side stop projecting outwardly of said plane forwardly thereof with respect to said housing and post and merging with said front face of said housing at its base, an arbor, said gear wheel being mounted on said arbor, said front face of said stop extending substantially perpendicularly to the axis of said arbor and said gear wheel.

4. The apparatus of claim 2 wherein said knife means is movable with respect to said stop substantially laterally alternately outwardly and inwardly with respect to said front face and sufficiently to alternately open said recess to receive a can bead therein as the latter moves above said stop and alternately press said gear bead against said wheel.

5. A can opener comprising a housing, said housing having an upper front opening and a lower rear opening, a pair of side walls and a member forming a continuous upper wall and rear wall interconnecting said side wall, a bridging wall positioned adjacent the front of said housing and defining in part said upper front opening, said bridging wall having a front surface, a gear wheel bearing against said front surface, an arbor connected to said gear wheel and extending through said bridging wall and said rear wall of said housing, means for rotating said arbor, a knife holder movably mounted within said housing and having a cutting wheel cooperable with said gear wheel for opening a can, said knife holder having an upstanding front wall continuation portion substantially closing said upper opening in said housing during normal cutting of a can, said knife holder being movable with respect to said gear for insertion and removal of a can intermediate said gear and a knife supported on said knife holder.

6. A can opener comprising a housing, a can-engaging gear positioned in said housing and having a portion

projecting upwardly thereof for engagement with a can positioned against said housing, a knife holder, said knife holder having a shaft slidably positioned therein, a knife rotatably mounted on one end of said shaft and bearing against said knife holder, resilient means connected to the other end of said shaft and said knife holder resiliently urging sliding movement of said shaft in said knife holder, said gear having an arbor connected thereto, said arbor and said shaft being positioned at an acute angle with respect to each other, said knife holder and arbor being substantially received within said housing and said knife holder having a portion thereof extending between spaced walls of said housing above said gear and forming a continuation of said housing, and means for rotating said arbor.

7. A can opener comprising a housing, a can-engaging gear positioned in said housing and having a portion projecting upwardly thereof for engagement with a can positioned against said housing, a knife holder, said knife holder having a shaft slidably positioned therein, a knife rotatably mounted on one end of said shaft and bearing against said knife holder, resilient means connected to the other end of said shaft and said knife holder resiliently urging sliding movement of said shaft in said knife holder, said gear having an arbor connected thereto, said arbor and said shaft being positioned at an acute angle with respect to each other, said knife holder and arbor being substantially received within said housing and said knife holder having a portion thereof extending between spaced walls of said housing above said gear and forming a continuation of said housing, and means for rotating said arbor, said housing including a bridging wall, said gear being mounted adjacent said bridging wall, said bridging wall defining an upper support, said knife holder resting on said upper support, a resilient means urging said knife holder to pivot with respect to said gear, said upper wall surface constituting means for resisting said pivotal movement.

8. A knife holder for a can opener comprising a housing, a first shaft opening extending through said housing, a second shaft opening extending through said housing laterally of the first mentioned shaft opening, said housing having a pair of depending legs extending downwardly adjacent one end of said housing and spaced apart to receive a can opener operating shaft, an upstanding wall portion extending upwardly from said housing in a direction substantially opposite the direction of extension of said legs and adapted to form a portion of an opener housing, boss means on said housing adjacent and concentrically disposed with respect to said first shaft opening and adapted to bearingly contact a rotary knife element.

9. The apparatus of claim 8 including a shaft supported in said first shaft opening, resilient means bearing against said housing and said shaft and urging movement of said shaft longitudinally of said bore, a rotary knife element rotatably fixed on said housing by said shaft, said knife element being resiliently urged against said boss means by said resilient means and having a peripheral cutting edge lying in a plane extending transversely of said shaft.

10. In a can opener, a housing for an operating mechanism, said housing comprising a pair of spaced side walls, a connecting wall connecting said side walls along a portion thereof and forming a rear and top wall, a bridging wall extending substantially parallel to said rear wall and from adjacent one edge of said side walls to the bottom thereof, said side walls forming a front face, said connecting wall extending at an angle to said front face of approximately 15 degrees, post means connected to said bridging wall and said side walls, said bridging wall, said side walls and said connecting wall forming a chamber having an upper forward opening and a lower rear

9

opening, means forming aligned openings in said bridging wall and said rear wall for supporting an arbor.
